F. NERGER.
RESILIENT HEEL.
APPLICATION FILED MAR. 1, 1919.

Patented May 3, 1921.

UNITED STATES PATENT OFFICE.

FREDERICK NERGER, OF CHICAGO, ILLINOIS.

RESILIENT HEEL.

1,376,965.

Specification of Letters Patent.

Patented May 3, 1921.

Application filed March 1, 1919. Serial No. 280,085.

To all whom it may concern:

Be it known that I, FREDERICK NERGER, a citizen of the United States, residing at Chicago, in the county of Cook and State of Illinois, have invented new and useful Improvements in Resilient Heels, of which the following is a full, clear, concise, and exact description, reference being had to the accompanying drawing, forming a part of this specification.

My invention relates to improvements in resilient heels and has for its object the production of a device of this character which will be adapted, when applied, to insure a close connection between the periphery thereof and the heel of the shoe in connection with which the same is employed. A further object is the production of a resilient heel which is capable of manufacture at a low cost, and which may be readily and easily applied for use. Other objects will appear hereinafter.

The invention will be best understood by reference to the accompanying drawings forming a part of this specification, and in which—

Figure 1 is a perspective view of a resilient heel embodying the invention;

Fig. 2 is an end view of the heel;

Fig. 3 is a bottom plan view of the heel applied to a shoe, a fragment only of the latter being shown;

Fig. 4 is a transverse section through a shoe and a heel embodying the invention, the arrangement here shown, disclosing the position of the heel just prior to securing the same in position; and

Fig. 5 is a perspective view illustrating the action of the heel when the lateral edges thereof are depressed to flatten the heel.

The preferred form of construction, as illustrated in the drawings, comprises a resilient body 6 of rubber or other suitable resilient material adapted for use in the forming of a resilient heel.

The heel 6 is molded into normally curved formation and is applied to the heel of the shoe A in connection with which the same is employed by means of nails or other suitable fastening devices 7 adapted to pass through openings or sockets 8 formed in the heel for the reception thereof. At the bases of the openings or sockets 8 are provided reinforcing perforated metallic plates or washers 9 which are molded in position in the heel and against which the heads of the

nails or securing devices are adapted to engage, as will be readily understood.

The curvature of the heel body 6 is, normally, in but one direction, this direction being transversely of the heel body and being cylindrical in nature,—that is, the heel body is formed or molded as though the same were but a section of a cylindrical tube, the transverse curvature thereof at any point being the same and a longitudinal section taken therethrough at any point being straight and non-curving. The curvature of the heel body is comparatively great, the same being preferably substantially 120 degrees.

With a heel body of this formation, it has been found, upon flattening of the same against a flat surface, such as illustrated in Fig. 5, where the heel body has been flattened through the pressure of the thumbs engaging against the opposite longitudinal edges of the heel, that the end portions 11 and 12 of the heel are caused to flex upwardly. This upward flexing of the ends 80 of the heel insures close engagement thereof with the adjacent edge portions of the shoe, when the heel is applied thereto. The extreme curvature of the resilient heel, as described, positively insures effective engagement of the lateral edges 10 thereof with the shoe inasmuch as the heel, when flattened, is distorted from its normal curved condition and the resiliency of the heel in its effort to return to its curved condition causes these 90 edges 10 to press very securely against the sides of the shoe.

With resilient heels of the formation now generally in use, the top of the heel is of a sort of dished formation,—that is, the same is curved or sloped in all directions toward the center of the heel so as to form a depressed upper heel surface. With this arrangement, however, flattening of the heel, in applying same, causes expansion of the 100 upper edge thereof. This being so, in the conventional type of heel, the curvature or degree of dishing of the heel is restricted, since if the dishing or concavity is too great, upon flattening of the heel, which, as mentioned, necessitates expansion of the upper edge thereof, the latter, it has been found, will be broken or ruptured inasmuch as the same is not capable of expansion to the extent or degree required. This restriction 105 in heels of the type now in use, prevents close contact being maintained between the

periphery of the heel and the shoe, inasmuch as the restriction as to the degree of permissible curvature of the heel, affects directly the pressure or tension of the heel relied upon to maintain this close contact.

With applicant's construction, however, wherein the heel body is curved in but one direction, this expansion of the upper edge of the heel in the flattening of the latter is eliminated with the result that the heel may be curved to any extent desired, thus making it possible to obtain practically any pressure or tension desired to insure the edge contact between the lateral portions of the resilient heel and the shoe to which the heel is applied. It is the lateral portions of the resilient heel which are most important, since it has been found that it is these portions of the heel periphery which usually do not maintain their close contact with the shoe heel, and with applicant's construction close contact at these points is positively insured and without any liability of rupturing or cracking of the heel in flattening the same during application.

As before mentioned, through the curved formation employed in applicant's construction, the front and rear end portions 11 and 12 are given a slight upward tendency in

the flattening of the heel, which serves to maintain these portions also in close contact with the shoe heel. With the latter portions of the heel, however, the maintenance of close contact through the inherent resiliency of heel is not so important, inasmuch as the front portion of the heel is under the shoe where the same is not seen, and the rear portion thereof is that which is continually receiving the brunt of the wear and pressure and hence is, therefore, continually being pounded or pressed into close contact with the shoe heel.

Having thus described my invention, what I claim as new and desire to secure by Letters Patent is:

A rubber heel having its upper face a circular cylindrical surface, the axis of which extends from front to rear, all vertical transverse sections forming arcuate intersections with said surface, said arcuate intersections being of equal radii, all vertical fore and aft sections forming rectilinear parallel intersections with said surface, the outline of the heel being shaped to conform to the outline of the adjacent portion of the shoe.

In witness whereof I have hereunto subscribed my name.

FREDERICK NERGER.
